RAZOR

William H. Ebelhare, Nichols, Conn., assignor to
 Magazine Repeating Razor Company, New
 York, N. Y., a corporation of New Jersey

Application February 5, 1940, Serial No. 317,322

3 Claims. (Cl. 30—40)

The object of the invention is a razor of the "magazine injector" type provided with stops for aligning a blade edge with the guard, in which provision is made for means that may be operated positively and unyieldingly to force the said blade edge against the said stops.

Referring to the drawing:

Fig. 1 is a top view of a razor embodying my invention, together with a magazine injector—parts being broken away from the razor to more clearly illustrate its construction;

Fig. 2 is a view on the line 2—2 of Fig. 1;

Fig. 3 is a top plan view of the razor with parts broken away to show the invention;

Fig. 4 is a view on the line 4—4 of Fig. 1.

Describing the drawing more in detail, the razor comprises a conventional handle 10 in which is socketed the shank 11 merging into the back plate 12, which in turn is bent over to form the top plate 13. The bottom plate, or blade support 14, terminates in the guard 15 and is an extension at right angles of the plate 16. The extension plate 16 is hingedly connected to the back plate by means of a hook 17 struck from the material of the back plate 12 and engaging in the aperture 18 the extension plate 16 and, by the lugs 19, 19, comprising turned-over portions of the back plate.

A spring for causing the bottom plate, or blade support 14 to bear upwardly against the top plate 13 for the purpose of clamping a blade 20 and also for causing the extension plate 16 to bear rearwardly toward the back plate 12 is pivoted to the shank 11 by any suitable means, such as the rivet 21, and is indicated by the numeral 22. The tip 23 of this spring bears upwardly against the blade platform and effects clamping of the blade 20 between the blade platform and the top plate 13. The bowed portion 24 of the spring bears rearwardly against the bowed portion 25 of the extension plate 16 and biases the extension plate rearwardly toward the back plate 12 as indicated at 26.

The guard is provided with blade stops 27, 27 against which the edge of a blade may be caused to abut, as may presently be described, and which serve to locate the edge of the blade definitely with relation to the guard 15. The struck-up ears 28, 28 are merely for the purpose of manipulating the main spring 22—i. e., to facilitate seizing it with the fingers to swing it on the pivot 21 so as to release tension on the blade platform and extension plate 16 to release a blade.

Affixed to the back plate 12 is a spring 30

anchored at each end to the back plate, one end being anchored by merely crimping the spring around the edge of the back plate, as shown at 31, and the other being anchored by the rivet 32. The anchorage 31 is, as will be observed by an inspection of Fig. 1, capable of slipping when the spring 30 is flexed toward the back plate and thus elongated slightly, as shown in Fig. 3.

Extending from the spring 30 is a finger 33 which projects through an aperture 34 in the back plate. The length of this finger is such that, when the spring 30 is in its normal position—i. e., its unstressed position or shape as shown in Fig. 1, it terminates at such a point so that the distance between its terminal and the stops 27 is greater than the width of the blades that are to be used in the razor. The finger 33 is also in line with the position that the blade occupies when positioned between the top plate 13 and the bottom plate 14.

The razor shown is of the so-called "magazine injector" type—i. e., the type in which a separate magazine is used, such as is shown in Fig. 1. To briefly describe such magazines, although they are already well known, it is sufficient to say that they comprise a boxlike receptacle 40 containing a stack of blades 41 and a slide 42 connected to a plunger 43 by means of the turned-over lip 44 extending from the plunger and through the slide and then turned over. As the slide 42 is moved to the extreme rear—i. e., to the right of the slot 45, it carries with it the plunger 43. Since the blades are spring-pressed in the direction of the slot, the plunger 43 engages the rear end of the top blade and by reverse stroke injects the blade into the head of the razor, at the same time ejecting a blade, if there be such, that is already in the head.

The magazine is also provided with an aligning finger 46 indicated by dotted lines (see Fig. 4), which finger is inserted in the slot 47 between the back plate 12 and the extension plate 16. The dimensions of this slot are such as to receive the finger 46 with a sliding fit so that, when the finger is inserted, the magazine is aligned with the razor so that a blade ejected from the magazine is properly aligned to enter between the top plate 13 and the bottom plate 14. In particular, it should be noted that the thickness of the finger is only such as to permit it to enter the slot freely but with a close fit—it not being in contemplation that there shall be any further separation of the extension plate 16 from the back plate 12 as a result of the insertion of the finger.

In explaining the operation, it may be assumed that the blade 20 (see Fig. 2) has just been inserted by operating the magazine in the manner above described and that the magazine finger has been withdrawn. It is then necessary to bring the blade edge in abutment with the stops 27, 27 in order that it may be properly aligned with the guard 15, this proper alignment having of course been predetermined. This is accomplished by pressing the spring 30 against its resistance toward the back plate by thumb or finger pressure, and this operation in turn through the medium of the finger drives the blade into abutment with the stops 27, 27, as shown in Fig. 3. The pressure of the top plate 13, which is of resilient material and construction is so adjusted as to retain the blade firmly in position with its edge against the stops while the implement is being used for ordinary shaving purposes. Release of the spring 30 from finger pressure causes it to return to its normal position, as shown in Fig. 1.

While I have described a certain particular construction in which my invention is incorporated, I do not desire to be limited to this particular embodiment since many changes and modifications may easily be made without departing from the spirit and scope of the invention as set forth in the following claims:

I claim:

1. A razor comprising a blade platform provided with a guard and with stops on the guard so positioned that a blade edge abutting them is in shaving position, a back plate terminating in a resiliently-pressed top plate for resiliently clamping a blade between the top plate and the blade platform, and a spring mounted on the rear side of the back plate and provided with a finger projecting through the back plate and aligned to exert a thrust against the rear edge of a blade 40

located in the blade channel between the top plate and the blade platform, said spring when unstressed being bowed rearwardly from the back plate sufficiently so that the terminal of the finger is substantially withdrawn from the blade channel.

2. A razor comprising a blade platform provided with a guard and with stops on the guard so positioned that a blade edge abutting them is in shaving position, a back plate terminating in a resiliently-pressed top plate for resiliently clamping a blade between the top plate and the blade platform, and a spring substantially bridging the back plate and provided with a finger projecting through the back plate and aligned to exert a thrust against the rear edge of a blade located in the blade channel between the top plate and the blade platform, said spring when unstressed being bowed rearwardly from the back plate sufficiently so that the terminal of the finger is substantially withdrawn from the blade channel.

3. A razor comprising a blade platform provided with a guard and with stops on the guard so positioned that a blade edge abutting them is in shaving position, a back plate terminating in a resiliently-pressed top plate for resiliently clamping a blade between the top plate and the blade platform, and a spring substantially bridging the back plate and provided with a finger projecting through the back plate and aligned to exert a thrust against the rear edge of a blade located in the blade channel between the top plate and the blade platform, said spring when unstressed being bowed rearwardly from the back plate sufficiently so that the terminal of the finger is substantially withdrawn from the blade channel, the said spring being slidingly anchored at one end.

WILLIAM H. EBELHARE.
